UNITED STATES PATENT OFFICE.

ARTHUR L. FRERET, OF ENSLEY, ALABAMA.

SAFETY SWITCH.

1,409,843.

Specification of Letters Patent. Patented Mar. 14, 1922.

Application filed May 22, 1918. Serial No. 235,924.

To all whom it may concern:

Be it known that I, ARTHUR L. FRERET, a citizen of the United States, residing in Ensley, Alabama, have invented certain new and useful Improvements in Safety Switches, of which the following is a specification.

This invention relates to electric switches coming generally under the head of snap switches or cut-out boxes and is designed particularly for use in connection with circuits of comparatively high potential such as motor and main line feeder circuits.

One of the objects of the invention is the provision of a switch structure having a protecting cover which cannot be opened unless the switch blades have been previously operated to break the circuit.

Another object is to provide a structure in which all the movable operating parts are carried by a hinged cover which can be swung clear of a fixed back base thereby giving free access to the terminals for adjustment or replacement of fuses without the liability of having the moving parts accidentally operated.

Other objects are attained in the embodiment herein described and shown in the accompanying drawings in which:

Fig. 1 is a front elevation of the improved switch with the front of the cover sectioned off as indicated by line 1—1 of Fig. 2;

Fig. 2 is a vertical sectional view taken on the plane indicated by the line 2—2 of Fig. 1; the switch blades and the enclosing cover being shown in their respective closed positions;

Fig. 3 is a view similar to Fig. 2 but showing the enclosing cover and the switch blades in their respective open positions;

Fig. 4 is a sectional view on the plane indicated by line 4—4 of Fig. 1 the switch blades however being shown in their open position in the interest of clearer illustration;

Fig. 5 is a detail view of the switch operating mechanism the parts being shown in the positions they assume when the switch blades are in closed position;

Fig. 6 is a similar view showing the positions assumed by the parts when the switch blades are in open position, being a section on line 6—6 of Fig. 4;

Fig. 7 is a detail showing the rectangular switch shaft with the switch blades secured thereto;

Fig. 8 is a detail perspective view of the operating dog; and Fig. 9 is a detail perspective view of the locking bar.

The switch comprises a fixed back plate 1 having an overhanging hood 2 secured thereto which comprises a top 3 and short side walls 4 and 5 and a front wall 6 extending downwardly therefrom. A hinged portion 7 formed in the front wall 6 forms a pivotal support for the enclosing cover 8 which cover includes side walls 9 and 10, a front wall 11 and a bottom wall 12. A lug 13 is formed integral with the front wall 11 of the hinged cover and a similar lug 14 is formed on the front wall 6 of the fixed portion of the casing. When the cover is in open position the apertures 15 and 16 in the respective lugs 13 and 14 will come into register and as shown in Fig. 3 the cover 75 may be securely held in open position by inserting a pin 17 through the registering apertures.

All the movable parts of the switch mechanism are supported by the hinged enclosing 80 cover and all electrical terminals and connections are carried or supported by the fixed back plate. It will thus be seen that when the cover is held in open position as shown in Fig. 3, that even though the switch 85 mechanism were accidentally operated no harmful results could occur, and it will further be noted that free access may be had to the terminals and switch jaws for replacement or repair or the renewal of fuses. 90

The hinged cover 8 is provided with a locking means actuated by the switch mechanism which co-operates with a stationary jaw secured to the back plate. This mechanism comprises a locking bar 18 guided in 95 brackets 19 and 20 secured to the side wall 9 of the cover. A spring 21 anchored to pins 22 and 23 carried respectively by the bar 18 and bracket 20 serves to normally keep the locking bar in the locked position 100 shown in Fig. 2. At its upper end the bar 18 is provided with an angular lip 24 for engagement with one of the trip pawls of the switch mechanism to be hereinafter described. 105

The lower end of the locking bar 18 co-operates with a lug 25' formed on the fixed bracket 25 which is secured to the back base 1 to securely hold the cover in locked position as long as the switch blades are closed 110 and in contact with their co-operating terminal switch jaws. When the switch mech-

anism is operated to break the circuit the locking bar 18 is raised to such position to permit the end of said bar to clear the locking lug 25.

6 The feeder terminals 26-26 enter the casing through suitable insulating bushings 27-27 in the top wall 3 of the casing 2 and are connected in the usual manner to the switch terminals 28-28 having downwardly 10 extending bifurcated jaws 29-29 which project into recesses provided therefor in the insulating block 30 which is suitably secured to the back base 1.

The motor leads 31-31 are connected to 15 the fuse terminals 32-32 secured to an insulating base 33 carried by the back base 1. Switch terminals 34-34 having jaws 35-35 are secured to the upper part of the insulating base 33 and suitable replaceable fuses 20 36-36 are interposed between other jaws 35'-35' of the switch terminals 34-34 and the jaws 32'-32' of the motor outlet terminals 32-32 in the usual well known manner.

An insulating barrier 37 is rigidly secured 25 to the back base 1 of the switch and is provided with a slot 38 concentric with the hinge 7 and terminating in an enlarged circular inner orifice 39. This slot cooperates with the shaft of the switch mechanism to 30 prevent the closing of the switch cover when the blades of the switch mechanism are in closed position, as will be hereinafter described.

The switch mechanism is carried wholly 35 by the hinged enclosing cover and is mounted therein in such a way that it can be easily and quickly removed for replacement or repair when necessary.

This mechanism comprises a detachable 40 unit or sub-assembly of parts including a shaft 40 the greater part of which is rectangular in cross-section as shown in Figs. 4 and 7. The ends of the shaft are cylindrical, one end 41 is supported in a bearing 42 45 which is detachably secured by screws 43 to the side wall 10 of the enclosing cover. The other cylindrical portion of the shaft 40, indicated at 44, is of greater length and is journalled in a suitable bearing formed in 50 the operating dog 45. The dog 45 is provided with a cylindrical hub portion 46 which is rotatably mounted within a suitable aperture in the side wall 9 of the hinged cover. By removing the bearing 42 the 55 whole switch mechanism can be taken out as a unit for inspection or replacement. The dog 45 (Fig. 8) is also provided with a square shank 47 for engagement with the operating handle 48, and an extended bifurcated jaw 49 for engagement with a tenon 50 of the control lever 50, which is loosely mounted on the portion 44 of the operating shaft 40.

On either side of the control lever (Figs. 65 4, 5, and 6) are located the oppositely wound

volute springs 51 and 52, the inner ends of which are fixedly secured to the shaft 44 and the outer free ends of which are hooked at 53 and 54 for engagement with the driving pin 55 carried by the control lever 50. A 70 ratchet 56 keyed to the operating shaft cooperates with trip pawls 57 and 58 which are pivotally secured at 59 and 60 to the side wall 9 of the hinged cover. The control lever 50 is provided with a projecting pin 61 75 adapted to alternately disengage the trip pawls 57 and 58 from the ratchet 56 and to also be engaged by the hooked tooth 58 of the trip pawl 58. An auxiliary trip cam 62 keyed to the cylindrical portion 44 of the 80 operating shaft is adapted to engage the pin 61 of the control lever to rotate the shaft 44 in the event that the spring snap mechanism should for any reason fail to operate.

Referring to Figs. 4 and 7, the switch 85 blades 63-63 and 64-64 are secured in dove-tailed slots 65-65 of the split supporting collars 67-67 which embrace the rectangular portion 40 of the operating shaft, and are insulated therefrom by layers of 90 fibre 68-68. Suitable bolts 69 securely clamp the collars 67 in position on the operating shaft. In Fig. 7 it will be seen that a line passing through the major axis of the cross-section of the shaft 40, is approximately at an angle of 45 degrees from a center line passing through the length of the blades 63.

When the switch is in closed position as illustrated in Fig. 2 with the blades 63-63 100 in the vertical position, the major axis of the rectangular section of the shaft 40 will be at an angle of approximately 45 degrees with the horizontal and coincident with a radial line passing through the hinge 7. In 105 this position, as more clearly seen in dotted lines at α in Fig. 3, it is clear that if for any reason the locking bar 18 did not operate to effectively lock the cover to the back base of the switch, that if an opening movement 110 were given to the cover the same would be prevented from opening by the interference of the shaft with walls of the orifice 39 formed in the barrier 37. However, when the switch blades 63 and 64 are in their open 115 position as indicated in Fig. 3 the blades and the shaft having been rotated through approximately 90 degrees will so position the rectangular portion of the shaft that the minor axis of its cross-section will be 120 opposite the arcuate slot 38 formed in the barrier 37. The slot being of greater depth than the minor axis of the shaft will permit the shaft to freely pass therethrough when the cover is raised to the open position as 125 clearly shown by the dotted position γ which indicates an intermediate position of the switch mechanism.

In operation when the switch is closed these parts are in the positions indicated in Figs. 130

1, 2 and 5, the hinged cover being locked in the closed position by the co-operation of the spring actuated locking bar 18 carried by the cover and the lug 25' of the bracket 5 secured to the back base 1. The cover 8 cannot be opened without first moving the switch blades to their open position by operating the handle 48 which act will raise the locking bar 18 by reason of engagement 10 between the lip 24 thereof with the trip pawl 57 which is raised to the position shown in Fig. 6 when the switch blades are opened. Should the locking bar 18 fail to operate through breakage or any other reason the rectangular portion of the shaft 40 will be in such position (as indicated at α in dotted lines in Fig. 3) as to prevent the passage of said shaft through the slot 38 which is of less width than the major axis 20 of the rectangular portion of the shaft.

When the switch blades are operated they quickly snap through an angle of approximately 90 degrees and their travel is arrested by coming into contact with rubber bumpers 70—70 carried by a lug 71 formed on the interior of the hinged cover. The opening movement is effected by turning the handle 48 which is carried by the squared portion 47 formed on the driving 30 dog 45 and its motion is transmitted by the bifurcated end 49 to the control lever 50 by engagement with a tongue 50a formed on the upper end of said control lever. As this lever is swung around in clockwise direction as indicated by the arrow in Fig. 5, the pin 55 carried thereby will come into engagement with the hooked end 53 of the spring 51 and a further movement thereof will wind said spring around the shaft 44

40 which at this time is held against rotation by the trip pawl 57 which is in engagement with the ratchet 56 secured to the shaft, the action of which is to store considerable torque within the volute spring 51. Continued movement of the handle 48 and control lever 50 will bring the pin 61 carried by said control lever into engagement with the underside of the trip pawl 57 and raise the same as shown in Fig. 6. This releases 50 the ratchet 56 and permits the shaft 44 and the switch blades carried thereby to be quickly snapped around into a position shown in Fig. 6 by the energy previously stored in the volute spring, the movement 55 of the switch blades being positively stopped by coming into contact with the rubber shock absorbing bumpers 70 carried by the ledge 71 of the cover. As the trip pawl 57 was being raised by the pin 61 carried by 60 the control lever 50, above described, its upward movement caused the locking bar 18 to be also raised due to the engagement of the lip 24 of the locking bar with the upper surface of the trip pawl 57, as indicated 65 in Figs. 2, 3, 5 and 6. With the switch

blades in this position the rectangular portion of the shaft 40 will be so positioned that it will freely pass through the slot 38 in the insulating barrier 37 and the locking bar 18 will be raised a sufficient distance to 70 permit its lower end to clear the tooth 25' on the bracket 25, thus rendering all the parts in position to permit the switch cover to be swung upward about its hinge 7 to the position shown in Fig. 3, to permit access to the interior of the switch. 75

To effect the closing movement of the cover, the switch blades must be in the open position as illustrated in Fig. 3 so that the rectangular portion of the shaft 40 will be 80 able to enter the slot 38 of the barrier and the locking bar 18 set to clear the tooth 25' of the locking bracket 25.

It is clear that should the switch handle 48 be inadvertently moved so as to bring the switch blades into closed position when the cover is open it will be impossible to swing the cover about the hinge 7 to a position whereby the switch blades will come into contact with the jaws 29 and 35 due to the interference of the rectangular portion of shaft 40 and the barrier wall 37, as indicated by dotted lines at α in Fig. 3.

After the switch cover has been closed down it may be additionally locked by a 95 suitable winged thumb screw 80 passing through a slot 81 in a depending lug 82 secured to the cover and entering a tapped hole in a similar lug 83 formed on the back base 1. The lugs 82 and 83 are provided 100 with registering apertures 84 through which a suitable padlock may be inserted to preclude the possibility of meddlers opening the switch.

When the cover is locked in the position 105 shown in Fig. 2, and the switch blades in the opened position indicated in dotted lines, the switch may be closed by swinging the operating handle in the direction indicated by the arrow in Fig. 6. The closing operation being very similar to the above described opening operation.

The driving dog 45 rotating the control lever 50 in the direction indicated permits the trip pawl 57 to fall into position to co-operate with the ratchet 56. Further movement causes the pin 55 to engage the hooked end 54 of the closing spring 52, storing energy in the said spring while the trip pawl 58 engaging the ratchet 56 prevents the rotary movement until the pin 61 of the control lever is swung around to a position to trip the pawl 58 from engagement with its co-operating ratchet whereupon the switch blades will be quickly snapped to the position shown in Figs. 2 and 5, the movement of the control lever being arrested by the pin 61 engaging the hooked end 58a of the trip pawl 58. 125

Provision is made for opening the switch 130

blades independent of the snap mechanism in the event that for any reason this mechanism should become inoperative due to the accidental breakage of one of the opening 5 springs or failure of other parts to properly operate. This auxiliary operating means comprises the cam 62 keyed or otherwise secured to the switch shaft. The pin 55 carried by the control lever 50 is of such length 10 that it projects within the path of said cam 62 as shown at the left of Fig. 4. As thus constructed it is clear that if for any reason upon the rotation of the control lever in the direction indicated in Fig. 5 the switch 15 blades do not operate, a continued movement thereof will carry the pin 55 around and into engagement with the cam 62 which being keyed to the shaft will cause the rotation thereof thus effecting an opening movement 20 of the switch blades.

Though I have described with great particularity of detail the embodiment herein shown, it is not to be construed that I am limited thereto, as it is clear that structural 25 changes may be made by those skilled in the art without departing from the spirit and scope of the invention as set forth in the following claims.

What I claim is:

30 1. An electric switch comprising a hinged enclosing cover, a quick operating snap switch mechanism carried thereby including switch blades carried by a shaft having a portion of non-circular cross section, a fixed 35 back base, a fixed barrier of insulation secured thereto and having a slot therein which co-operates with said non-circular portion of said shaft to prevent the cover being either opened or closed when the 40 switch blades on said shaft are in closed position.

2. An electric switch comprising a hinged enclosing cover, a quick operating snap switch mechanism carried thereby including 45 switch blades carried by a shaft having a portion of non-circular cross section, a fixed back base, a barrier secured thereto having a slot therein which co-operates with said non-circular portion of said shaft to prevent 50 the cover being either opened or closed when the switch blades on said shaft are in closed

position and means actuated by said snap switch mechanism whereby the said enclosing cover is locked to said fixed base when the switch is closed and unlocked therefrom 55 when the switch is open.

3. In an electric switch a fixed back base, an enclosing cover hinged thereto, a slotted insulating barrier secured to said back base, a snap switch mechanism carried by said hinged cover having an operating shaft of non-circular cross section, means for quickly imparting a partial rotation of said switch shaft, the non-circular shaft and the slotted insulating barrier being so associated that 60 when the switch blades are in closed position the shaft will be so positioned that the walls of the barrier will prevent the cover from being swung on its hinge.

4. In an electric switch a fixed back base, 70 an enclosing cover hinged thereto, a quick snap spring actuated switch mechanism carried thereby having a shaft of non-circular cross section, a barrier secured to said fixed back base having a slot therein adapted to 75 either prevent the opening or closing of said cover when the switch blades are in closed position, and a locking mechanism carried by said cover and associated with said switch mechanism and arranged to be locked and 80 unlocked thereby when the blades thereof are moved respectively in their closed and open positions.

5. In an electric switch, a fixed back base, 85 a cover hinged thereto, switch terminals carried by said back base, a shaft detachably mounted in said cover which is provided with at least two sets of switch blades and means for effecting a quick opening and closing movement of said blades, and a dielectric barrier secured to said back base and located between said switch blades and terminals to prevent arcing or short circuiting between said terminals or switch blades, said barrier having a slot formed therein to permit the free passage of the shaft therethrough when the switch blades are in open 90 position substantially as described.

In witness whereof, I have hereunto signed my name.

A. L. FRERET.
